(57) **CLAIM**

The ornamental design for an organizer rack, as shown and
described.

DESCRIPTION

FIG. 1 is a top, front, left-side perspective view of an
organizer rack showing my new design;
FIG. 2 is a front elevational view thereof;
FIG. 3 is a left side elevational view thereof;
FIG. 4 is a right side elevational view thereof;
FIG. 5 is a rear elevational view thereof; and,
FIG. 6 is a top plan view thereof; the bottom plan view being
a mirror image thereof.
